UNITED STATES PATENT OFFICE.

ELDON L. LARISON, OF ANACONDA, MONTANA.

ACID PLANT.

1,334,384.

Specification of Letters Patent. Patented Mar. 23, 1920.

Application filed February 10, 1919. Serial No. 276,217.

To all whom it may concern:

Be it known that I, ELDON L. LARISON, a citizen of the United States, residing at Anaconda, in the county of Deerlodge and State of Montana, have invented certain new and useful Improvements in Acid Plants, of which the following is a specification.

This invention relates to an improved form of construction for towers and chambers for the manufacture of sulfuric acid.

It has heretofore been the custom and considered necessary to support the lead curtain walls and tops of such towers and chambers by means of independent wood or steel structures, whether or not such towers or chambers contained interior masonry walls or packing. These methods have involved heavy and expensive framing especially in those cases where it was desirable to use towers or chambers of considerable height.

I propose the construction of towers or chambers in which masonry walls are used or packing is employed, in such a way that the lead sheathing of sides and tops with the necessary light framing to which the supporting lead straps are attached, shall be supported on the masonry walls.

This method of construction is especially adapted to large units in which it is necessary to use towers or chambers of such height that simple and cheap framing is not adequate. In standard methods of construction the wood or steel members to which the lead sheets are directly attached are usually light and small, but they in turn must be supported by heavy wood or steel framing. It is the object of this invention to avoid the use of these latter heavy and expensive frames in building high structures of this kind. I propose however to use the standard methods of supporting the lead sheets in so far as they are suitable.

In the accompanying drawings,—

Figure 1 is an elevation, partly in section, the section being taken on plane A—A of Fig. 3;

Fig. 2 is a plan, partly in section, the section being taken on plane C—C of Fig. 3;

Fig. 3 is a sectional elevation on plane B—B of Fig. 2;

Fig. 4 is an enlarged end view of the corbel support;

Fig. 5 is an enlarged front view detail of the corbel support;

Fig. 6 is a plan of Fig. 4.

The sulfuric acid chamber itself comprises

end walls 1, side walls 2 and transversely arranged interior masonry walls 3, all resting on the foundation 4. The chamber may be provided with a masonry packing 5. This entire structure is surrounded by a lead curtain 15 which is supported on a relatively light framework. This framework comprises beams 10 supported by the masonry in the manner hereinafter described, these beams extending along the sides and ends of the chamber. As shown, the beams 10 are arranged about midway the height of the chamber; but where higher chambers are desired two or more such beam supports 70 spaced at proper distances may be provided.

The horizontal beams 10 are supported as shown in Figs. 3 and 4 by one or more corbel supports 17 extending outwardly from the ends of the transverse walls 3, the lead curtain however extending between the beam 10 and the corbel 17. In order to prevent the internal gas pressure from pushing the beams 10 off the corbel supports, truss rods 20 are anchored at their lower ends in the foundation 4, as shown in Fig. 3, and at their upper ends are secured to the channel bars 40. Bearing against the beams 10 are timbers 22 provided on their outer ends with caps 21 secured by bolts 23. The truss rods 20 pass over these caps and are given the proper tension by means of the turn buckles 24.

The intermediate framework to which the lead curtain is secured by lead straps 16 comprises a series of vertical struts 13 having their ends secured to horizontal members 18—18 and 19—19. The members 18—18 are secured, as by spiking, to beam 10; and of the two members 19—19, the upper one is secured to the beam 10 and the lower by dowel pins or otherwise to the concrete foundation.

Longitudinally extending straps or bars 9 and 11 extend entirely around the structure 100 and serve to hold the vertical struts 13 in place.

The roof portion of the curtain is supported by longitudinally extending bars 12 to which it is secured by lead straps 16. 105 These bars 12 extend from a cross piece 7 supported on the upper ends of the struts 13 to channel bars 40, which are preferably arranged immediately over the transverse walls 3, as shown in Fig. 1, so as to be supported thereby. The roof structure may be braced by rods 14, as shown in Fig. 2, and

also by fastening the side members to the channel bars 40 by clip-angles riveted to the channel bars 40 and bolted through the members 8. The entire framework on which the lead curtain is supported is itself thus directly carried by the foundation and the interior masonry structure of the sulfuric acid chamber.

The form of construction above described is especially adapted to large units where it is necessary to use chambers of such height that simple framing is not adequate, and heavy framing becomes very expensive. In the cases of towers or chambers of small horizontal section, small shelves of corbel construction may be provided at suitable vertical intervals on the corners of the masonry lining walls for the support of the horizontal members of the frames to which the lead is attached.

In order to avoid dead spaces devoid of gas and acid circulation, in which spaces compounds of nitrogen injurious to lead are likely to be formed, it will be noted that a

space of several inches is left between the 25 lead sheathing and the interior masonry side walls, in which space gas or acid may be allowed to circulate.

I claim:

1. A chamber for use in the manufacture 30 of sulfuric acid comprising interior masonry walls, and a lead sheathing supported by said walls and by a framework to which the sheathing is connected, said framework comprising members supported by said 35 walls.

2. A chamber for use in the manufacture of sulfuric acid as claimed in claim 1 in which members of the framework are supported on corbeled shelves extending from 40 the interior masonry walls.

3. A chamber for use in the manufacture of sulfuric acid as claimed in claim 1 in which the framework is held in position by means of tensioned truss rods. 45

In testimony whereof, I affix my signature.

ELDON L. LARISON.
